UNITED STATES PATENT OFFICE.

LEVI M. BOWMAN, OF FORT WORTH, TEXAS, ASSIGNOR TO CHARLES M. HERRING, OF FORT WORTH, TEXAS.

PIN-HOLDER.

1,183,848.

Specification of Letters Patent. Patented May 23, 1916.

Application filed July 2, 1913. Serial No. 777,125.

To all whom it may concern:

Be it known that I, LEVI M. BOWMAN, citizen of the United States, residing at Fort Worth, in the county of Tarrant and State 5 of Texas, have invented new and useful Improvements in Pin-Holders, of which the following is a specification.

This invention has for an object to simplify the manufacture of a casing and mechanism for dispensing pins, whereby the device will be salable at a price which will bring it within the range of popular demand.

A further object is to provide a novel construction of container for a roll of pins and the paper from which pins have been removed and a guide means for presenting the pins for removal.

A further object is to enable the ready removal of the pins without manipulation of any apparatus, and without requiring mechanism for checking the pins individually.

A further object is to provide such a device adapted to be of utility for other functions besides the dispensing of pins from the package.

Additional objects and advantages will appear, some of which will be apparent 30 from the following description and from the drawings, showing one embodiment of the invention, in which,

Figure 1 is a front elevation of the device, Fig. 2 is a top view thereof, Fig. 3 is a similar view with covers removed, Fig. 4 is a bottom view, Fig. 5 is a fragmentary vertical section of the reeling device.

There is illustrated a rectangular base 10 pressed from sheet metal, of oblong form, 40 including a top 11 and inclined sides 12. The base is oblong in plan, and set thereon there is a casing 13 formed of one strip of sheet metal bent to form two circular receptacles 14 and 15 adjacent respective ends 45 of the base, and a connecting passage 16 leading from one to the other. The lower edge of the strip is secured in any customary manner to the base 10, being flanged on the inside and soldered, as shown. The attenuated portion of the casing inclosing the

passage 16 is held with its sides in proper relative position by means of two rivets 17 located adjacent the top and bottom of the casing respectively, and which in addition serve to perform functions to be subsequently explained. The casing is closed over the receptacles by means of respective covers or caps 18, having flanges 19 on their under sides fitting snugly within the sides of the receptacles, the flanges being interrupted in registry with the passage 16, the abutting ends of the flanges being curved outward to fit in the beginning of the passage adjacent each, the sides of the casing being curved gradually outward from the 60 arc of the major part of the receptacles and converging gradually to form the passage 16. The covers have each a flange 21 projecting beyond the sides of the casing whereby it may be readily lifted. On top of the 70 covers there are provided circular pin cushions, 18', for which the shape of the device is particularly adapted, although they are not an essential element of the invention. The base 10 is extended farther 75 in front of the casing 10 than behind, and a small tray 22 may be formed therein, in which loose pins may be disposed. The tray as shown has the central portion cut away as at 23, on each side of which opening flanges 80 24 are turned upwardly having alined notches in which pins 25 may be laid.

The sides of the casing directly above the rivets 17 have alined notches 26 therein, of a size suitable to conform to the end of a 85 finger tip approximately. Mounted for rotation concentrically of the receptacle 14 there is a spindle 27, having at its lower part close to the top of the base 10 a disk 28. Similarly mounted in the opposite receptacle there is a winding drum 29, comprising a block of cylindrical form having a slot 30 extending throughout its length and inclined opposite the direction in which the drum is to rotate normally, as will be 90 described. The drum is carried on a shaft 31 projected beneath the base and provided with a gear 32 fixed thereon close against the under side of the base. Carried revolvably by the base immediately beneath the 100

entrance to the passage 16 from the receptacle 15 there is a stub shaft 33, having a suitable grip 34 for turning it, provided with a ratchet 35 immediately adjacent the under side of the base engaged by a spring 5 pressed pawl 36 to hold the shaft against rotation in one direction. Revoluble on the shaft there is a large gear 37 and connected by respective ends to the gear and shaft there is a spring 38. The gear 37 is meshed 10 with the small wheel of a double gear 39, carried by the base, the large wheel 40 of which is meshed with the gear 32. Nothing holds the drum against rotation under 15 action of the spring except the pin paper, as will be described, and nothing interposes to check rotation of the gear train.

The pins are obtained fixed transversely 20 in a paper ribbon 41, wound spirally upon itself, and in charging the device the roll of pins is presented in the receptacle 14 with the points downward, the spindle 27 being engaged through the center of the roll. The outer end of the ribbon strip should be 25 previously fed through the passage 16 between the rivets 17 from the receptacle 14 to the one 15, in the latter of which its extremity is inserted in the slot of the drum and the latter rotated sufficiently to take up 30 some of the ribbon, or at least to turn the part engaged in the slot at a considerable angle to that without the slot. The roll containing the pins being in place on the spindle and disk 27 and 28, and the covers 18 being engaged in the receptacles the device 35 may be inverted and the key 34 operated to put the spring 38 under sufficient tension. This will result in winding up all of the outer 40 end portion of the ribbon 41 containing no pins until the first of the pins in the package is drawn into the passage 16. The ribbon is of such breadth that the pins project beyond each edge, and the rivets are spaced, the lower so as to support and guide the ribbon 45 horizontally, and the upper one a short distance above the ribbon. The projecting portions of the outermost pin of the roll are thus brought into engagement with the respective rivets under rotation of the drum 50 29, and these rivets being located on a vertical line adjacent or slightly beyond the axis of the notches 26, which extend some distance below the level of the pin-heads, the head of the first pin is presented centrally of 55 the notches in the most convenient position for extracting. The gear train and drum being otherwise free to rotate and the spring 38 being under constant tension, tending to wind the drum, the removal of the outermost pin will always result in releasing the ribbon and movement of the ribbon until the 60 succeeding pin is brought against the rivets 17 in turn.

It will be apparent that an extremely simple and inexpensive device is provided, the

operation of which, for charging with pins is so simple as to involve no difficulty in being understood by persons without mechanical aptitude, and which involves absolutely no complications in manipulation for 70 extraction of pins.

The applicant is aware of such construction as that shown in the patent to Ormond, #615,885, for dispensing pins, and also the patent to Lawton and Withey, #810,952, and 75 does not claim such construction, but that hereinafter set forth.

The particular form of base described is not essential of course, and if desired may be made only large enough to close the lower 80 ends 14 and 15. In the latter case the bottom element may be spaced some distance from the lower edge of the device in the receptacle 15 and the spring and gear train made of such size as to be accommodated within the space beneath the bottom, and within the receptacle as shown in Fig. 5.

While the device is described as formed of sheet metal, the joints being soldered, of course it is within the scope of the invention 90 if the parts are formed with any other material secured together by any other means than that mentioned. The device may be constructed of celluloid, which may be found preferable.

What is claimed:

1. A pin dispensing device comprising a casing having a reeling and an unreeling chamber and a connecting passage having a finger receiving opening at its upper side 100 extending downwardly a distance, vertically spaced check elements fixed in the casing beneath said opening, means to carry a roll paper of pins in the unreeling chamber, a drum in the reeling chamber for winding 105 pin paper from the unreeling chamber, and means constantly tending to rotate the drum, whereby the outermost pin will be held against said check elements with a portion projecting through said opening.

2. A device of the class described comprising a base element, a casing thereon, comprising a single strip of sheet metal bent to form two circular loop portions comprising receptacles, and parallel connecting portions forming a passage communicating with the receptacles, said parallel portions being provided with intermediate aligned notches at their upper edges, closure means for the upper sides of the receptacle, means for supporting a roll of pins to be unwound in one receptacle, means for reeling a pin carrying ribbon from the other receptacle, and means for checking the outermost pin of a roll being unwound in alignment with 120 the notches.

3. A pin dispensing device comprising a casing having a reeling and an unreeling chamber and a connecting passage having a finger receiving opening at its upper side extend- 130

ing downwardly a distance, vertically spaced
check elements fixed in the casing beneath
said opening, means to carry a roll paper of
pins in the unreeling chamber, a drum in the
5 reeling chamber for reeling the pin carrying
element from the unreeling chamber, and
means to rotate the drum.

In testimony whereof I have hereunto set
my hand in presence of two subscribing wit-
nesses.

LEVI M. BOWMAN.
